(57) **CLAIM**

The ornamental design for a water bottle, as shown and described.

DESCRIPTION

FIG. 1 is the first perspective view of a wafer bottle showing our new design;

FIG. 2 is the second perspective view thereof;

FIG. 3 is a third perspective view thereof, showing the design in its open position;

FIG. 4 is a perspective thereof with the lid shown separately to show aspects of the design that may not be apparent in the other views;

FIG. 5 is a right side view thereof of open state of the design of FIG. 8, showing the design in its open position and the handle feature in an alternative configuration;

FIG. 6 is a front view thereof;

FIG. 7 is a rear view thereof;

FIG. 8 is a right side view thereof;

FIG. 9 is a left side view thereof;

FIG. 10 is a top plan view thereof; and,

FIG. 11 is a bottom plan view thereof.

The broken lines in the figures illustrate portions of the water bottle that form no part of the claimed design.
